UNITED STATES PATENT OFFICE.

OLIVER AVERY, OF GROTON, NEW YORK.

REVERSE-GEAR FOR ENGINES.

SPECIFICATION forming part of Letters Patent No. 319,051, dated June 2, 1885.

Application filed February 20, 1885. (Model.)

To all whom it may concern:

Be it known that I, OLIVER AVERY, of Groton, in the county of Tompkins and State of New York, have invented certain new and useful Improvements Reverse-Gears for Engines; 5 and I do hereby declare the following to be a full, clear, and exact description of the invention, such as will enable others skilled in the art to which it pertains to make and use it, reference being had to the accompanying drawings, which form part of this specification.

My invention relates to an improvement in reverse-gears for engines in which a slide valve is used; and it consists in the combination of the driving-shaft, the pulley secured thereto and having a slot or slots through its ends, the eccentric having a slide and inclined guides secured thereto, inclined guides placed inside of the pulley and extending at 15 an angle to those secured to the eccentric, the followers which move upon the guides, and the sliding sleeve which is connected to the followers, as will be more fully described hereinafter.

25 The object of my invention is to use only one eccentric in reverse-gears for steam, gas, and hydraulic engines in which a slide-valve is used, whereby the eccentric can be shifted from one side of the shaft to the other, so as 30 to reverse the revolutions of the driving-shaft and enable a variable cut-off to be obtained.

Figure 1 is a longitudinal section of a reverse-gear embodying my invention. Fig. 2 is an end view of the pulley and the parts 35 placed inside of it, the sleeve being removed. Fig. 3 is an end view taken from the opposite end. Fig. 4 is a similar view to Fig. 2, the followers and sleeve being removed. Fig. 5 is a perspective of the followers. Figs. 6, 7 40 are detail views. Fig. 8 is a side elevation of my gear, a part of the pulley being broken away.

A represents the driving-shaft, and B the pulley secured thereto. One end of the pulley is open and the other one is closed, and the closed end forms both a face-plate, C, and a hub, *a*, for the pulley. Upon this face-plate 45 the slide D moves back and forth when the eccentric is shifted from one side of the shaft to the other. Through this end C are formed four slots, which have their inner ends parallel with each other, and their outer edges

on an angle to correspond to the angle on the lugs K. The slots are slightly longer than the lugs, in order to allow of an end movement 55 of the guides L and to allow lost motion to be taken up.

The slide D is made in a single piece with the eccentric G, and has a slot, H, made through it for the hub of the pulley to pass 60 through, and so that the slide can move freely back and forth across the end of the pulley. The slide is held in place upon the end of the pulley by means of the guides J', which are secured to the end plate, C, by means of suitable bolts. In order to assist in keeping 65 these guides in place, each one is provided with a lug or projection, K, to fit in corresponding holes in the end plate, C.

Secured to the slide are the two inclined 70 guides L, which pass through the slots T and the followers M, and which cause the eccentric to move across the shaft at every end-wise movement of the followers. As the slide is moved across the face of the end of the pulley, the movable inclined guides are moved 75 correspondingly through the pulley.

In the pulley are also two other guides, N, which extend in opposite directions, or at any suitable angle to the other guides, L; but 80 which, instead of being movable, are stationary. In this case they are secured to the inner side of the pulley; but they may be secured to any other part. The object of the guides is to prevent the followers from being 85 carried back and forth in the pulley with the two movable guides L, and to cause the followers to move diagonally endwise in the direction of the length of the shaft. Two of each of the inclined guides are here shown 90 and described; but only one of each may be used, if so preferred. Where two are used, as here shown, the followers are more perfectly supported and guided in their movements than where only of each kind is used. 95

The followers are applied to opposite sides of the shaft, but free from it, and are secured together by means of the bolts O, and by means of which bolts the followers can be drawn closer together from time to time in order to 100 take up the wear. Each of the followers is cut out on its inner side, as shown, so as to fit over the inclined guides and to move freely back and forth upon the them. These fol-

lowers M move diagonally across the shaft at whatever pitch the inclines are set, the two movable inclined guides being secured to the slide and the slide secured to the eccentric. A 5 horizontal movement of the followers, at the same time that they are being carried or moved diagonally across the shaft to the extent of the inclination of one set of inclined guides, causes the eccentric to move a distance equal to the 10 inclination of both sets of guides. In other words, if the pitch or inclination of both sets of guides is the same, then while the follower moves one inch the eccentric moves two. In order to allow this movement, the openings 15 through the followers are elongated, so as to be equal to the pitch or inclination of one set of guides, while the opening through the slide and eccentric is equal in length to the amount of inclination on the two sets of guides. 20 Projecting from the outer ends of the two parts of the followers are the two bolts P, which pass through the two slotted arms or extensions of the slide Q, which is applied directly to but not fastened to the shaft. To 25 the outer side of the two slotted arms are applied the washers R and the nuts S. The two arms are slotted so as to allow the bolts P to move diagonally across the shaft with the followers. Applied to the outer end of this 30 slide is a loose sleeve, T, which is provided with the lugs U, to which the reverse or controlling lever is fastened. This sleeve is placed loosely on the slide, so as not to be affected by the revolutions of the slide, which 35 revolves with the shaft A. The slide with the slotted arms answers the double purpose of allowing the followers to move across the shaft diagonally, and to prevent the sliding friction between the followers and the slotted 40 arms from reacting on the reverse-lever when the eccentric is in motion.

A movement of the reversing-lever causes the slide to move the followers and the followers to move the slide D and eccentric G, and thus shift the eccentric from one side of 45 the shaft to the other. By shifting the eccentric from either extreme of its throw toward its guide-gear, at the same time keeping the lead of the valve the same, a shorter cut-off is obtained. 50

The eccentric is here shown as moving straight across the shaft; but it may move in a circle across or have a swinging movement.

Having thus described my invention, I claim— 55

1. The combination of the sleeve to which the reversing-lever is connected, the slide having the slotted arms, the bolts secured to the followers, the followers, the inclined guides, and the slide and eccentric, substantially as shown. 60

2. The combination of the pulley having its end form both a face-plate and a hub, and provided with slots for the movable inclined guides to pass through, with the slide D, eccentric, and the guides J, applied to the end of the face-plate, substantially as shown. 65

3. The combination of the pulley having one end formed into a face-plate, the stationary inclined guides, and the movable inclined guides, the followers, and the slide which is moved by the reversing-lever, substantially as set forth. 70

In testimony whereof I affix my signature in presence of two witnesses.

OLIVER AVERY.
